TRAIN ORDER ANNUNCIATOR.

No. 480,073.

Patented Aug. 2, 1892.

UNITED STATES PATENT OFFICE.

LEONARD T. CRABTREE, OF EMBARRASS, WISCONSIN.

TRAIN-ORDER ANNUNCIATOR.

SPECIFICATION forming part of Letters Patent No. 480,073, dated August 2, 1892.

Application filed October 15, 1891. Serial No. 408,743. (No model.)

To all whom it may concern:

Be it known that I, LEONARD TRACY CRABTREE, of Embarrass, in the county of Waupaca and State of Wisconsin, have invented 5 a new and useful Improved Train-Order Annunciator, of which the following is a full, clear, and exact description.

This invention relates to improvements in apparatus for indicating to engineers and conductors of railroads that train-orders await delivery at stations on the line of road which have been sent by telegraph from a main station.

The object of this invention is to improve 15 the construction of the train-order annunciator for which Patent No. 448,125 was granted to me, dated March 10, 1891. In said patented invention a casing is shown wherein a series of slides are supported in parallel horizontal planes which are movable independently, each slide being marked with a numeral or other symbol that when exposed before an aligning aperture in the front wall of the casing by manipulation of the slide bearing 20 said numeral will indicate the number of a train or engine that is to receive orders. The annunciator-case of the patented device also contains a vertical sliding gravity-bar, which is held elevated by insertion of a 25 pencil through its upper end, which style or pencil it is imperatively required that the operator shall use in writing all messages received on the relay or telegraph instrument.

To permit elevation of the gravity-bar, all 35 indicating-slides are moved away from the sight-holes in the casing front wall, so that no orders will thus be indicated, and at the same time the circuit between the line-station and main station will be closed, so as to 40 permit the free transmission of dispatches to the line-station from the main office.

When orders are sent, the operator at the receiving-station must use the "style" that holds the gravity-bar elevated to copy the 45 dispatch, which by its removal from the bar allows the latter to drop, and this cuts out the relay from the main line until a visual signal is set to notify trainmen that orders await an approaching train, the act of 50 setting said signal serving to close the cir-

cuit, so that the operator may receive a message.

The present invention contemplates additional features of improvement whereby an audible signal will be provided which will automatically operate to notify trainmen that orders await them within the station-office in case the visual signal that is also provided has been unnoticed. 55

The improvements, furthermore, will indicate to a train-dispatcher in charge at a main office if the station-operator is alert at his post when a dispatch has been sent with regard to moving trains, and also if he complies with rules as to manipulation of the train-order 60 mechanism, so as to properly receive and notify trainmen with regard to orders that may await delivery at the station. 65

To these ends my invention consists in certain features of construction and combinations of parts, as is hereinafter described, and pointed out in the claims. 70

Reference is to be had to the accompanying drawings, forming a part of this specification, in which similar letters of reference indicate 75 corresponding parts in all the figures.

Figure 1 is a front elevation of the annunciator-casing broken transversely and having the front wall removed, showing interior parts and circuit-wires connected thereto. Fig. 2 80 is a diagrammatic view of the apparatus, parts being shown in section and others broken away. Fig. 3 is an enlarged vertical section taken on the line 3 3 in Fig. 2, parts being shown broken away and their adjustments by 85 dotted lines. Fig. 4 is an enlarged detached sectional detail showing the construction of a circuit-closer for a signal-bell. Fig. 5 is an enlarged transverse section taken on the line 5 5 in Fig. 2, and Fig. 6 is a front view of a 90 modified construction of the current-changer from that shown in Fig. 2.

The annunciator-case A is shown broken away, removing a middle portion and also some of the interior parts, said removed portions being fac-similes of others that are shown. A rectangular form is given to the case A, and within it the gravity-bar B is held to slide vertically by a loose engagement of its end portions with aligning apertures 95 100

formed in the top and lower walls of said case. The upper part of the gravity-bar B slides through a boss a' , that projects above and upon the top wall a , and the lower end portion b , that similarly engages the lower wall, 5 is rounded and reduced in diameter, producing a shoulder at b' , sufficient length being given to the cylindrical portion b to allow a proper longitudinal movement of the gravity-bar. Parallel with the gravity-bar B a releasing slide-bar C is loosely engaged at its ends with the top and lower walls of the case A, said end portions having a cylindrical form of reduced diameter. On the upper end 10 of the slide-bar C, that projects a proper distance above the top wall a , a button-head a^2 is secured, which limits the depression of the bar, and the shoulder a^3 , that engages the inner side of the case-top wall, determines its 15 upward movement, which latter is effected by a spiral spring c, that encircles the lower cylindrical portion c' of the slide-bar and engages the shoulder c^2 thereon. Transversely of the casing A a series of similar indicator-20 plates d are supported to slide in parallel planes. One of said planes is shown in position in Fig. 1. The indicator-plates d each rest on a cross-strip d' , that is secured within the case A, which strips have their thickness 25 reduced on the portion below the indicator-plates to equal that of the latter, and thus adapt the strips to receive each a pusher-bar d^2 , whereon a plate-spring d^3 is secured by one end, its free end projecting upwardly to 30 engage with ratchet-teeth d^4 , cut in the lower edge of the indicator-plate it bears upon. The pusher-bars d^2 each rest on a base-strip d^5 , so as to be permitted a reciprocal movement 35 that is limited inwardly by the impinge of its end on the shoulder d^6 , formed on the cross-strip d' . The other end portion d^7 of the pusher-bar projecting through the side wall of the case A is reduced diametrically and rounded to receive a spiral spring d^8 , which 40 engages the button-head d^9 on the outer end of the pusher-bar, and by its expansive force holds the pusher-bar against the side wall of 45 the case with which it is engaged.

On the top of each indicator-plate d a pull-bar e is securely located in a longitudinal groove, said bars aiding to retract the plates if draft force is applied to their outer ends. 50

The gravity-bar B is made thicker than the slide-bar C, considered from front to rear of the case A, and the latter-named piece slides 55 through the cross-strips d' and base-strips d^5 behind the indicator-plates, as represented in Fig. 1.

At proper intervals a series of pins e' are 60 secured in the slide-bar C, which pins each have a bearing upon the upper surface of a plate-spring d^3 and work in a vertical slot made in the cross-strip d' , so that a depression of the slide-bar C will release the ends 65 of the plate-spring from the ratchet-cut teeth in the indicator-plates d and allow any one of said plates to be adjusted transversely of the

case A and locate any one of the numerals on its face in front of a sight-hole f, formed in the front wall A' of the case A, there being 70 such a sight-aperture formed therein for each indicator-plate.

With the exception of the boss a' on case A and the formation given to the ends of the slide-bar C and the provision of the spiral 75 spring c, which causes an elevation of said bar, the parts so far described are similar to parts exhibited in Patent No. 448,125.

At a proper point from the top end of the gravity-bar B a transverse hole is made for 80 the introduction of a style B', which is in form adapted for use to write manifold copies of a telegraph-message, being in pencil form, the introduction of which style will hold the bar in elevated adjustment. 85

Upon the bracket-arm g, that projects from the side wall of the case A within and rearward of the gravity-bar B, a cylindrical dash-pot D is supported, which has a small perforation in each of the heads, as at g' in Fig. 1, 90 and within the dash-pot a piston-head g^2 is located that is attached upon one end of a bent rod g^3 . The latter-named piece, projecting through the upper head of the dash-pot, is secured by its upper end to the gravity-bar 95 and is adapted, in conjunction with the piston-head and cylindrical pot, to cushion the movement of the bar B in either direction of its travel. Below the bracket-arm g an elastic metal plate E is affixed by one end on a 100 binding-post h, that is secured to the lower wall of the case A, and projects through it a sufficient distance to sustain the plate E upon its upper end slightly above the upper end of another binding-post h', that is located near 105 to the post h and projects in a similar manner through the lower wall of the case.

The spring-plate E should be a good electric conductor, and is given a proper length to allow it to receive the lower cylindrical 110 portion b of the gravity-bar B, that passes loosely through a hole made in the plate near its free end.

On the exterior of the side wall of the case A, that supports the bracket-arm g, 115 and above the latter, a binding-post h^2 is affixed and projects within the case, and on its inner end a metal conductor-strip h^3 is clamped by its lower end, the upper terminal of the strip being located on short stud h^4 , 120 whereon the lower end of a contact-spring i is placed, these pieces being lapped and held on the stud by a screw or other means. The upper end of the spring i has electrical contact with the lower end of a conductor-strip 125 i', that is held in position by an adjacent stud i^2 , which projects inwardly from the side of the case A, the upper terminal of the strip i' being secured upon the inwardly-extended end portion of a binding-post i^3 , that is inserted through the side wall of the case near 130 its top wall a. The contact-spring i is reinforced by a plate-spring i^4 , which is secured to the inner surface of the case side wall by

one end, the free end of said reinforce-spring pressing against the spring i , so as to insure the latter having a positive contact with the end of the strip i' .

5 On the edge of the gravity-bar B that is opposite the conductor-strip i' a series of preferably V-shaped notches are cut, which are so spaced apart as to produce intervening projections k , the spaces between which are 10 graduated to represent some of the dots and dashes of the Morse alphabet.

Upon the upper end of the contact-spring i a finger-bar k' is attached by one end, the other end portion of said bar being loosely 15 supported by a swing-bar k^2 , that is jointed at its upper end to the inner side of the case-wall a and by its lower end to the finger-bar, as shown in Fig. 1. The terminal k^3 of the finger-bar k' is shaped to freely enter the 20 spaces between the tooth-like projections k on the gravity-bar B and traverse the same when the gravity-bar is allowed to fall, thus by a longitudinal reciprocation of the finger-bar causing a make and break of contact between the contact-spring i and the end of the 25 conductor-strip i' .

Near the shoulder b' on the gravity-bar B an electric contact-bar b^2 is inserted through the bar projecting on each side, and to the 30 end that is nearest to the binding-post h^2 a wire b^3 is joined, that is extended to have connection with the inner end of the post named.

There is a binding-post c^3 inserted through the lower wall of the case A, and upon its upper end a bell-crank lever F is pivoted to rock, the terminal c^4 of its short arm being opposite the inner end of a binding-post c^5 , that is extended from without through the side wall of the case that is engaged by the ends 40 d^7 of the pusher-bars d^2 .

The long arm of the bell-crank lever F projects toward the gravity-bar B, and when the latter is in an elevated condition the lever-terminal c^6 rests upon a projecting pin b^4 , that 45 is a short distance removed from and below the contact-bar b^2 .

The long arm of the bell-crank lever F is pressed upward by a spring G, that is seated on the bottom of the case A and secured there- 50 to by one end, the tension of the spring causing the terminal c^4 of the short arm to impinge upon the post c^5 when the gravity-bar B is elevated and so retained by the style B'.

All of the binding-posts and studs that form 55 supports for parts, as described, are suitably insulated from the case-walls to prevent transmission of electricity from one to the other through said walls, which may be of metal or other material.

60 The annunciator-case A is secured in an upright position within the telegraph-office of a way-station, and one of these is supplied for each station to which train-orders are to be sent. In the office is also placed a receiving telegraph-instrument I, a switchboard J, a current-changer K, and, preferably, a circuit-closer L, or the latter may be stably sup-

ported on the outside near the office. A signal-bell M is also placed at a proper elevation near the railroad-track exterior of the office, 70 and a device to operate the circuit-closer and cause the bell to ring is placed near to the track, so as to be moved by car-wheels of a train. These parts will be hereinafter described and their co-operative action explained. 75

The relay-instrument I, of usual form, is connected by wires m and posts m' to a local sounder, (not shown,) which is a usual fixture in a telegraph-office. 80

At a proper point on the office wall or other stable support the base-block n of the current-changer K is secured. This device consists, essentially, of a lever n' , that is secured on a transverse shaft n^2 , which is journaled in 85 bracket-lugs n^3 , that project from the front face of the block. The lever n' is weighted at its lower end and is furnished with a hook n^4 at its upper end. On a projecting end of the rock-shaft n^2 a crank n^5 is secured. Upon the 90 rear side of the base-block n , which is recessed, two contact-plates o are secured therein, which plates lie parallel to each other and to the top and bottom edges of the block projecting from one side edge n^6 of the base-block 95 toward the opposite edge n^7 . The binding-posts o^1 o^2 are projecting from the front side of the base-block n , through it, and are each secured to one of the plates o , said posts being located near the edge n^6 of the base-block. 100

Near the side edge n^7 a binding-post o^3 is inserted through the block n , and on its rear end a contact-plate o^4 is affixed. Said post being rotatable in the block has a short arm o^5 projected from its side, which arm is pivoted at its free end to a link-bar o^6 , that is secured in like manner at its lower end to the outer end of the crank n^5 . The lever n' is held 105 normally projected away from the base-block n by a spring p , and the attached parts are so adjusted that contact-plate o^4 will be rocked to have contact with the upperplate o , on which is the post o' , when the lever is thus projected, 110 as shown by full lines in Figs. 2 and 3. It is designed that the base-block n be placed near 115 to a pendent cord O, which is shown broken, but in service extends to be attached to a signal-blade or other device of like character that is located exterior of the telegraph-office, near or over the railroad-track, so as to indicate orders awaiting within the office, if said blade 120 (not shown) is in a projected condition, which will be effected by a draft on the cord and the hooked attachment of its ring or loop O' on the hook n^4 of the lever n' .

When the visual signal, that may be a semaphore-blade or a flag, has been displayed by the means stated, the lever n' will be rocked into the position shown by dotted lines in Fig. 3, and the contact-plate o^4 will then be 130 moved so as to bear upon and have electrical connection with the lower spring-plate o , to which the post o' is affixed.

The switchboard J is of usual form and is

connected to main-line wires N at q , and from one post q' on the board a wire P is extended to connect said board with the post o^3 on the the current-changer K, a conductor-wire P', that is attached to another binding-post q^2 , extending to the binding-post i^3 on the annunciator-case A.

On the wall R of the telegraph-office which is nearest the railroad-tracks SS' or on some support exterior of and removed from said office a circuit-closing device L is secured, which consists of a box or similar support that will serve as a base, whereon the binding-posts r r' are fixed. One post r' has an armature-bar r^2 , pivoted to its lower end, so that the bar may swing downwardly and away from the lower end of the other post r , on which it will bear if rocked upwardly. A spring-plate r^3 is secured upon and projects beyond the free end of the armature-bar r^2 , and near the outer extremity of the plate a depending rod r^4 is attached by its upperend, said rod having a spring r^5 on it that engages with one end the lower wall of the box on which the posts r r' are placed and with the other end a collar on the rod, whereby the armature-bar will be depressed when the spring is free to act.

Above the circuit-closer L or at any other preferred point a signal-bell M, adapted to be rung by an electric current, is located. One post s on the bell has the terminal of a wire U secured to it, said wire having its other end connected with the binding-post h on the annunciator-case A, the other post s' on the bell M being electrically connected with the binding-post r on the circuit-closer by a wire U'.

A local battery T is provided to work the apparatus, and from the post r' on the circuit-closer L a wire V is extended to join one pole of said battery, the other pole having a wire V' in connection, which wire extends to join the binding-post h' on the annunciator-case A.

The binding-post o' on the current-changer K is connected by the wire W with post c^3 , and from the post c^5 on the case A a wire X extends to the post u on the sounder I, and a wire X' connects said post u with the post o^2 on the current-changer K. Between the post h^2 on the annunciator-case A and the post u' on the sounder I a conductor-wire Y is extended. A horizontal shaft S², supported in suitable bearings, so as to allow it to rock, extends from a point adjacent to the lower end of the upright rod r^4 outwardly and close to the rail S' of the track, and on the inner end a crank-arm v is secured, which latter has its pin v' loosely connected with the lower end of the rod r^4 . Upon the other extremity of the rock-shaft S² an arm w is formed and lies adjacent to the track-rail S' and is adapted to receive the impact of a flange on a car-wheel or truck-wheel on a locomotive, the arm being preferably provided with a head-plate w', whereon the wheel-flange will bear.

The arrangement of parts just described is such that the spring r^5 , in normal condition, will hold the crank-arms v rocked downwardly 7c and the arm w inclined upwardly so that pressure on the latter will elevate the crank-arm v and the rod r^4 , and thus close the circuit between the battery T and bell M.

The elevated adjustment of the gravity-bar 75 B will cause the short arm of the bell-crank lever F to electrically connect with the post c^5 and bring the posts c^3 c^5 into connection, also, which will establish a connection with the switchboard J through the upper contact-plate o, contact-plate o^4 , post o^3 , and wire P. In this position, the train-order signal not being elevated, the circuit is from J to o^3 , through P, thence to post c^3 , through plates o^4 , o, post o' , and wire W, from post c^5 to post u on the sounder I, through wire X, thence through the relay to post u' , thence by wire Y to post h^2 , thence through conductor-strip h^3 , spring-strip i, and strip i' to post i^3 , and thence through wire P' to the switchboard J. When 90 the gravity-bar B is lowered, the circuit is through the wire P, plates o^4 and o, post o' , wire W, post c^3 , the long arm of lever F, bar b^2 , wire b^3 , plates h^3 , i, and i' , and spring i^4 to post i^3 , and by the wire P to the switchboard J. The circuit between the battery T and bell M is open at r, as before stated, when the arm w is not pressed down, and there is a break of electrical connection between the battery and bell produced while the 100 gravity-bar B is held elevated by the engagement therewith of the style B'. Consequently there will not be an audible signal given on the bell until the bar B is in lowered adjustment, which will cause the plate E to bear 105 upon the post h' , as indicated in Fig. 2. The fall of the gravity-bar B will break the connection of the bell-crank arm with the post c^5 , and thus cut out the sounder I until the lever n' is rocked and held in position by the 110 cord O, that is then drawn upon, so as to elevate the signal (not shown) over the railroad-track.

In some systems of train-signaling the pulling of a cord or vibration of a lever will set the 115 signal to indicate "safety" in place of "danger." Should it be desired to employ such a method of signaling in conjunction with this improved train-orderannunciator, the current-changer K is slightly altered in arrangement 120 of its parts, as will be seen by referring to Fig. 6. The change consists in extending the shaft n^2 toward the edge n^7 of the base-block n and placing the crank n^5 on this extended portion, so that the link-bar o^6 will be allowed to pivotally connect the pin of said crank with the short arm o^5 , which latter is projected oppositely or toward the edge n^6 of the base-block n. 125

When the parts of the current-changer are 130 arranged as just described, the rocking of the lever n' into the position shown by dotted lines in Fig. 3 will rotatably move the contact-plate o^4 , so as to connect it with the post o' ,

- and thus establish the circuit the same as is effected in Figs. 2 and 3, in which the lever n' is in a perpendicular position to indicate "safety." The depression of the gravity-bar 5 B causes its projections k to successively engage the toe k^3 of the finger-bar k' , and thus make and break the connection of the contact-spring i with the conductor-strip i' , and as its supporting-strip i^3 is electrically connected by the wire P' to the switchboard J , it is evident that a Morse alphabetic signal will be sent to the main office, and thus indicate when the bar B is lowered, and for the purpose of rendering such signals distinct the 15 dash-pot D is of service, as it cushions the fall of the bar in an obvious manner, the speed of descent being regulated by the size given to the orifice g' in the bottom wall of the dash-pot.
- 20 Each office on the line will have a separate alphabetic symbol to designate it. Hence the automatic sending of such a signal, as explained, will enable the train-dispatcher at the main office to know when the way-station 25 operator removes his style, and as the operator cannot receive a message until the visual signal is displayed, there is a double safeguard afforded to prevent a train or engine from being run past a station where there are 30 orders to be delivered.

The indicator-plates d are to be set for the right train, and the correct numeral thus exposed at a sight-hole f to indicate the number of orders awaiting delivery to an engineer or 35 conductor of the signaled train or engine.

Having thus described my invention, what I claim as new, and desire to secure by Letters Patent, is—

1. In a train-order annunciator, the combination, with a battery and a telegraph receiving-instrument, of a train-order recording and indicating device, a current-changer that will hold a visual signal exposed, a signal-bell, electric connections between the battery telegraph-instrument, recording-device bell, and current-changer, and a normally-open circuit-closer electrically connected to the bell, battery, and order-recorder, that will be mechanically closed by impact of a car-wheel, substantially as described.

2. In a train-order annunciator, the combination, with a battery, a switchboard, main-line wires, a receiving-instrument, a train-order recorder and indicator, and wires connecting these devices electrically, of an electrically-connected signal-bell, a normally-open circuit-closer, and a mechanical device connecting the circuit-closer with a rock-shaft and treadle-arm thereon, that will be depressed by impinge of wheels on a locomotive or car, close the circuit, and ring the bell, substantially as described.

3. In a train-order annunciator, the combination, with a battery, a switchboard, main-line wires, a receiving-instrument, a train-order recorder and indicator, a current-changer, and wires connecting all these devices elec-

trically, of a cord or other operating device for a visual signal, which may be connected to the lever of the current-changer and hold it rocked, a normally-open circuit-closer, a signal-bell, wires to connect the bell with the circuit-closer, battery, and order-recorder, and a mechanical device which will close the circuit and cause the bell to ring when engaged by the wheel of a locomotive or car, substantially as described.

4. In a train-order-annunciator apparatus, a current-changer comprising a rocking lever on a base-block, a rock-shaft supporting the lever, a crank-arm thereon, two separated spring contact-plates supported on binding-posts, a shifting contact-plate which is secured on a rotatable binding-post and that may engage either spring-plate, an arm on said post, and a link-bar loosely connecting this arm with the crank-arm of the rock-shaft, substantially as described.

5. In a train-order-annunciator apparatus, a recording and exhibiting device comprising a case, movable indicator-slides therein having numerals that may be exposed before sight-holes in the front of the case, a vertically-adjustable gravity-bar, means to move the indicator slide-plates longitudinally, a 95 rocking bell-crank lever supported on a binding-post that will engage its short arm with another post when the gravity-bar is elevated, a contact-bar on the gravity-bar that will engage the long arm of the bell-crank 100 when the gravity-bar is depressed, a binding-post bearing a spring contact-plate that will be depressed when the gravity-bar falls, and another binding-post that will be engaged by the spring contact-plate when the gravity- 105 bar falls, substantially as described.

6. The combination, with a case, a gravity-bar adapted to slide vertically in the case, a removable style that supports the bar elevated, a series of separated projections formed 110 on one side of the gravity-bar, and a dash-pot device connected with the bar, of a finger-bar supported to swing and loosely engage the projections on the gravity-bar with one end, and a contact-plate that is actuated to make 115 and break a closed electric circuit by the other end of the finger-bar when the gravity-bar falls, substantially as described.

7. In a train-order annunciator, the combination, with a case having an apertured front 120 wall, indicator slide-plates numbered in series which when slid will expose a number before an aperture, a pusher-bar for each slide-plate, and a spring on each pusher-bar that engages its free end with teeth on the 125 edge of a slide-plate, of a vertical slide-bar, pins on said bar that will compress the springs on the pusher-bars when the slide-bar is depressed, and a spiral spring below on the slide-bar that holds it normally elevated, substantially as described.

8. In a train-order-annunciator apparatus, the combination, with a signal-bell, a battery, an annunciator-case, a gravity-bar vertically

movable in the case, a binding-post on the case supporting a contact spring-plate that is loosely engaged by the lower end of the gravity-bar, another adjacent binding-post where-
5 on the contact-plate will be imposed when the gravity-bar falls, a circuit-closer comprising a box, two binding-posts thereon, to one of which a circuit-closing bar is hinged by one end and adapted to bear on the other post when swung upwardly, and connecting-wires between the bell binding-posts, battery, and posts on the annunciator-case, of a rod depending from the circuit-closing bar, a spi-

ral spring on said rod which holds it and the circuit-closing bar normally depressed, a rock-
15 shaft below having a crank on one end connected with the depending rod, and an arm on the other end of the rock-shaft near a track-rail, which will be depressed and close the circuit when impinged upon by a car-
20 wheel, substantially as described.
